UNITED STATES PATENT OFFICE.

B. F. SWEET, OF FOND DU LAC, WISCONSIN.

IMPROVEMENT IN CAR-COUPINGS.

Specification forming part of Letters Patent No. 33,612, dated October 29, 1861.

To all whom it may concern:

Be it known that I, B. F. SWEET, of the city and county of Fond du Lac, in the State of Wisconsin, have invented a new and useful Improvement in the Construction of Car-Couplings; and I do hereby declare that the following is a full, clear, and exact description of the same, reference being had to the annexed drawings, making part of this specification, in which—

Figure 1 is a side view of a draw-head with a link and bolt, all being constructed and arranged according to my invention; Fig. 2, a vertical section of the same, taken in the line $x x$ of Fig. 4; Fig. 3, a plan or top view of the same, and Fig. 4 a front view of the same.

Similar letters of reference indicate corresponding parts in the several figures.

This invention relates to an improvement in the construction of the ordinary car-couplings, and has for its object economy of construction and durability—results which it is believed are obtained in a much greater degree than by the ordinary modes of construction.

The invention consists in having the front parts of the draw-heads which receive the link or shackle of cast-iron and having the plates or bars fitted therein by dovetails and secured by a shrunken wrought-iron band, substantially as hereinafter fully shown and described.

To enable those skilled in the art to fully understand and construct my invention, I will proceed to describe it.

A A represent the top and bottom plates or bars of the draw-head of a railroad-car, the former being attached to the latter in the usual or in any proper way. The plates A A are of wrought-iron, and they are provided at their front ends with dovetail terminals $a a$, which are fitted in corresponding recesses $b b$ in the upper and lower surfaces of the body B of the draw-head. The body B of the draw-head is of cast-iron, of circular form, and the front ends of the plates or bars A A are firmly secured in the recesses $b b$ of the body B of the draw-head by means of a wrought-iron band C, which is shrunk in the body B. This will be fully understood by referring to Fig. 4, in which the dovetail

terminals $a a$ of the plates A A are shown fitted in the recesses $b b$ and encompassed by the band C. The body B of the draw-head has an elliptical opening c, which has a flaring or beveled front d to admit of the link or shackle D passing freely into it, (see Fig. 2,) and a pin E, which passes vertically through the plates A A, retains the link or shackle D in the head, as will be fully understood by referring to Figs. 1 and 2. The pin E fits in a groove or recess d' at the back part of the body B of the head, and said groove or recess serves to steady the pin in proper position when fitted in the plates or bars A A. The body B of the draw-head, being of cast-iron, is hard and durable and not capable of being battered and worn by the action of the link or shackle D, while the plates or bars A A, being of wrought-iron, are rendered capable of sustaining all lateral and vertical strain to which they may be subjected.

The construction of the draw-head as shown and described is extremely simple and durable.

Draw-heads cast in one piece or entirely of cast-iron are very liable to break, the plates or bars A A not being able to resist a great lateral strain. Draw-heads constructed wholly of wrought metal are very expensive and not very durable, as the body B is rather soft and liable to become bruised or battered by the action of the link or shackle D. By having the body B of cast-iron and the plates A A of wrought-iron, the latter being secured to the body B by dovetail connections and a shrunken wrought-iron band C, an economical and durable draw-head is obtained.

Having thus described my invention, what I claim as new, and desire to secure by Letters Patent, is—

Constructing the draw-heads of railroad-cars by having wrought-iron plates or bars A A fitted by means of dovetail connections in cast-iron bodies B and secured therein by shrunken wrought-iron bands C, substantially as shown and described.

B. F. SWEET.
